(57) **CLAIM**

The ornamental design for a camera lens cover, as shown and described.

DESCRIPTION

FIG. 1 is a front perspective view of a first embodiment of a camera lens cover showing my new design in a closed state;

FIG. 2 is a front view thereof;
FIG. 3 is a rear view thereof;
FIG. 4 is a left view thereof;
FIG. 5 is a right view thereof;
FIG. 6 is a top view thereof;
FIG. 7 is a bottom view thereof;
FIG. 8 is a front perspective view thereof shown attached to a smartphone camera;
FIG. 9 is a front perspective view of the camera lens cover of FIG. 1 in an open state;
FIG. 10 is a front view thereof;
FIG. 11 is a rear view thereof;
FIG. 12 is a left view thereof;
FIG. 13 is a right view thereof;
FIG. 14 is a top view thereof;
FIG. 15 is a bottom view thereof;
FIG. 16 is a front perspective view thereof shown attached to a smartphone camera;
FIG. 17 is a front perspective view of a second embodiment of a camera lens cover showing my new design in a closed state;
FIG. 18 is a front view thereof;
FIG. 19 is a rear view thereof;
FIG. 20 is a left view thereof;
FIG. 21 is a right view thereof;
FIG. 22 is a top view thereof;
FIG. 23 is a bottom view thereof;
FIG. 24 is a front perspective view thereof shown attached to a smartphone camera;
FIG. 25 is a front perspective view of the camera lens cover of FIG. 17 in an open state;
FIG. 26 is a front view thereof;
FIG. 27 is a rear view thereof;
FIG. 28 is a left view thereof;
FIG. 29 is a right view thereof;
FIG. 30 is a top view thereof;
FIG. 31 is a bottom view thereof;
FIG. 32 is a front perspective view thereof shown attached to a smartphone camera;
FIG. 33 is a front perspective view of a third embodiment of a camera lens cover showing my new design in a closed state;
FIG. 34 is a front view thereof;
FIG. 35 is a rear view thereof;
FIG. 36 is a left view thereof;

(Continued)

FIG. 37 is a right view thereof;
 FIG. 38 is a top view thereof;
 FIG. 39 is a bottom view thereof;
 FIG. 40 is a front perspective view thereof shown attached to a smartphone camera;
 FIG. 41 is a front perspective view of the camera lens cover of FIG. 33 in an open state;
 FIG. 42 is a front view thereof;
 FIG. 43 is a rear view thereof;
 FIG. 44 is a left view thereof;
 FIG. 45 is a right view thereof;
 FIG. 46 is a top view thereof;
 FIG. 47 is a bottom view thereof;
 FIG. 48 is a front perspective view thereof shown attached to a smartphone camera;
 FIG. 49 is a front perspective view of a fourth embodiment of a camera lens cover showing my new design in a closed state;
 FIG. 50 is a front view thereof;
 FIG. 51 is a rear view thereof;
 FIG. 52 is a left view thereof;
 FIG. 53 is a right view thereof;
 FIG. 54 is a top view thereof;
 FIG. 55 is a bottom view thereof;
 FIG. 56 is a front perspective view thereof shown attached to a smartphone camera;
 FIG. 57 is a front perspective view of the camera lens cover of FIG. 49 in an open state;
 FIG. 58 is a front view thereof;
 FIG. 59 is a rear view thereof;
 FIG. 60 is a left view thereof;
 FIG. 61 is a right view thereof;
 FIG. 62 is a top view thereof;
 FIG. 63 is a bottom view thereof; and,
 FIG. 64 is a front perspective view thereof shown attached to a smartphone camera.

The broken line showing of the camera is for the purpose of illustrating environmental structure and forms no part of the claimed design.
